UNITED STATES PATENT OFFICE.

PETER WELCH AND AUDLEY MURPHY, OF OLEAN, NEW YORK

WAVE FILTER RECEIVING CIRCUITS.

Application filed February 6, 1925. Serial No. 7,292.

This invention relates to improvements in radio receiving systems, and particularly to means for increasing the efficiency of operation of a detector system.

- 5 This invention comprehends the provision of a secondary anode in a translating device used for detecting radio signals operable in an output circuit of the device independent of a primary output circuit containing a 10 sound reproducer, which is adapted to increase the efficiency of operation of the device and the receiving system by providing a leakage path for the discharge of the device and relieving the load on the input circuit and the grid, in addition to which a 15 leakage path is provided for oscillation which frequently interrupts and interferes with the efficient reception of a desired signal.
- 20 The invention comprehends numerous other objects which are more particularly pointed out in the following detailed description and claim directed to the preferred form of the invention, it being understood 25 however, that various changes in the invention may be made without departing from the spirit and scope thereof as herein set forth.

In the drawings forming part of this application:—

Figure 1 is an elevational view of a translating device constructed in accordance with this invention.

Fig. 2 is a wiring diagram showing the 35 translating device illustrated in Fig. 1, provided with circuit connections for an input and an output circuit for operating the sound reproducer in the output circuit in accordance with a signal impressed on the input 40 circuit, said circuits being of a type generally known in the art, in the improvement forming this invention being shown in association therewith.

1 indicates a vacuum tube constructed for 45 use as a detector tube, having a pair of series connected filament sections 2 forming the cathode of the tube, a pair of grids 3 arranged at opposite sides of the filament sections 2 and interconnected as indicated 50 at 4, and finally provided with a connection to the terminal 5 of the tube. The filament sections 2 are connected to a pair of terminals 6 and 7 in the usual manner, in order that the filaments may be interposed in a 55 suitable circuit with a source of energy 8 adapted to be controlled by a rheostat for

heating the filament sections to incandescence.

A pair of plates 10 and 11 forming the primary and secondary anodes of the tube 60 are mounted at opposite sides of the filaments and also the grids as illustrated in Fig. 1 of the drawing, the primary anode 10 having electrical connection with the positive terminal of the source of energy 65 24, while the secondary anode 11 is preferably connected to the positive end of the filament as indicated at 13 within the body of the tube.

If desired, an additional contact may be 70 provided on the base of the tube for receiving a circuit connection from the secondary anode 11, in order that an exterior circuit may be connected with the anode in the event it is desired to use an inductance, 75 capacity, or resistance, or a combination of either in the circuit between the anode 11 and the positive filament connection for assisting in the operation of the tube in clearing the energy received in the input circuit 80 of oscillations which are not desired in the output circuit of the primary anode.

Fig. 2, showing the wiring diagram, of 85 a regenerative circuit illustrates for example an antenna circuit indicated by the numeral 14 generally, which includes a variable capacity 15 and a variable tuning inductance 16, with the usual ground connection 17.

The input circuit to the electron discharge 90 device 1 includes the inductance 16 having the usual connection 18 with the double grid 3, 3 and the grid return circuit connected through the wire 19 to the positive side of the filament circuit at 23.

The output circuit of the device includes 100 a connection 20 with the primary anode 10 a feed back coil 21, the sound reproducer 22 and a suitable source of potential 24 having the positive terminal connected so as to impress the anode 10 with positive potential, while the negative terminal of the source of energy 24 is connected to the filament circuit at the point 23.

It is to be understood that the input and 105 output circuits of this electron discharge device as above described, are of the usual type well known in the art and may be of any other desired design of the several types now used in the art.

The present invention comprehends particularly the provision of the secondary an-

ode 11 having the direct connection as indicated at 25 in Fig. 2, with the positive terminal of the cathode or filament 2, as a result of which it will be energized with a positive potential with respect to the cathode equal to the potential of the source of energy 8, which is always of a considerably smaller value than the positive potential used for impressing a positive charge on the primary anode 10.

As a result, a secondary output circuit is provided by this invention, thru the secondary anode 11, while the grid 3 common to the input circuit will control the transfer of energy from both the primary and secondary anodes in accordance with the variations of potential in the input circuit.

It is found from actual experience that in the operation of the invention as herein set forth, the signals impressed on the output circuit connected with the primary anode 10 and reproduced in the sound reproducer 22, are cleared to a substantial extent of the undesirable sound resulting from static disturbances impressed on the antenna circuit, or interference from stations of a different wave length.

It should therefore be readily understood that the provision of the secondary anode 11 having the direct electrical connection with

the positive terminal of the cathode as well as a connection with the ground through the wire 19 serves to increase the efficiency of operation of a translating device used for detecting radio signals.

What is claimed is:

In a radiant energy receiving system, an electron discharge device having a filamentary cathode, a grid, a primary anode, an input circuit including the grid and cathode; an output circuit including the primary anode, cathode, a sound reproducer and a source of potential for applying a positive potential to said primary anode; a source of energy connected with said cathode, a secondary anode in said device having direct electrical connection with the positive terminal of said cathode and energized with a positive potential by the source of energy connected with the cathode, the potential impressed on the secondary anode being substantially less than that applied to the primary anode, said grid controlling the transfer of energy from each anode, and a ground connection with said secondary anode.

In testimony whereof we affix our signatures.

PETER WELCH.
AUDLEY MURPHY.
